TENNIS RACKET WITH PNEUMATIC
TIGHTENERAntonín Rauch and Václav Smolík,
Prague, CzechoslovakiaApplication March 8, 1934, Serial No. 714,694
In Czechoslovakia March 30, 1932

1 Claim. (Cl. 273—73)

This invention relates to a tennis racket with pneumatic tightening of the gut stringing carried out according to the invention in such a manner, that round the fixed, inner frame and handle 5 of the racket, one or preferably two parallel rubber tubes are located, filled with compressed air; these tubes consist either from one single piece, or conveniently of two interconnected air pipes, or tubes, connected or tied together by a ligament. 10 The stringing of the racket is held together and adjusted by the usual means, such as hooks, or the threading through of the racket frame etc., to the outer rim of the racket frame, which consists of several independent segments, movable 15 respectively to each other and to the inner frame, and is tightened or loosened by inflating or deflating the air tubes.

On the accompanying drawings an embodiment of the invention is given by way of example, with 20 the corresponding details and alternative solutions thereof. Fig. 1 shows schematically the elevation of the racket in section along line I—I in Fig. 2; Fig. 2 is a side-view of the tennis racket with a double rubber tube, Fig. 3 is a longitudinal 25 axial section led through the handle of the racket with the gear, connecting the air pipes and showing the relief valve and the piston, located nearly in its upper position, omitting the frame. Fig. 9 shows a detailed side-view of the racket part of 30 Fig. 3, Figs. 4 to 8 show five different devices for holding the gut stringing on the pneumatically tightened frame, all in cross section.

The tennis racket consists, according to the invention, of a stiff inner frame 10 of the usual 35 oval shape, which is provided below with a fork-extension 12, to which a hollow handle 14 is connected. All round the outer circumference of this inner frame 10 a slot 16 runs, having a rounded canal section (Figs. 4 to 7) or two similar slots 40 running parallel to each other (Figs. 2 and 8), in each of which an elastic air tube 18 of usual circular cross section is placed. On the outer circumference of the stiff frame 10 and beyond the tube 18, or both parallel air tubes 18 is set 45 a number of segment rim-pieces 20 along the tubes, either between both lateral parallel flanges 10' (Figs. 1, 2, 4 and 5) of the inner frame 10 or themselves provided with parallel flanges 20', which cover the tube 18 laterally, as well as the 50 stiff inner frame 10.

The rubber tube 18, or each of both tubes 18 lying side by side, is divided on the top, i. e. at the point opposite to the handle 14; each tube 55 consists thus of two branches, the ends of which may be tightened and provided with a ligament

24. The other ends of the tubes are connected together and fitted to a common piping 26, extending between the sideplates 12 of the handle 10 and reaching to a connecting pipe 28, fitted to a relief valve 30 (Fig. 3), serving to close the 5 tube in a way as described below.

The connection of the tube 26 with the pipe 28 is effected by means of a conical screw-socket 32 provided with an outer thread (Fig. 9), on which a tightening nut 34 may be screwed. This 10 nut ensures an absolutely fixed and immovable connection between the tube extension 26 and the valve pipe 28. The valve needle 36 of the relief valve 30 in the pipe 28 extends up to the middle of the hollow part 38 of the handle 14, where a 15 piston 40 is placed; the piston rod 42 of the piston is terminated on its outer free end by a handle 44, which may be fixed in the normal position by means of a bayonet fastening 46. Inside the hollow piston rod 42 of the piston, a spindle 48 (Fig. 20 3) is provided, the inner end of which is flattened and located in the space above the piston, whilst its outer end is provided with a button 52, set in a depression 54 of the piston handle. Under the button of this spindle a return safety spring 56 is 25 placed in the said depression for a purpose hereinafter described.

The racket strings 58 of the gut stringing may be fixed to the outer segmental rim parts 20 of the frame in various manners, as may be seen in 30 Figs. 1, 2, 4 to 8. In the alternative arrangements according to Figs. 1 and 2 the gut stringing is threaded through apertures in the movable parts of the rim 20; these strings are suspended on a 35 number of hooks 60 on the part of the frame lying at the top of the handle, whilst the outer free parts of the rim 20 are interrupted at this place to enable the removal of the tubes from inside the frame by loosening the ligaments 24; the ligaments serve besides to pull these tubes back 40 into the frame groove after effecting the repair or exchange thereof.

In the alternative according to Fig. 4, the stringing 58 is led over a small pulley wheel 62 suspended freely on a wire stirrup 64, adjusted 45 in a transverse slot 66 of the outer rim 20 of the racket frame.

According to Fig. 5, the gut of the racket stringing is directly threaded through a similar transverse slot 66.

In the arrangement shown in Fig. 6, the pulley wheel 62 is placed on a transverse spindle 68, adjusted on both lateral flanges 20' of the corresponding rim 20 of the frame.

In the alternative mode according to Fig. 7, 55

both lateral flanges 20' of the rim segments 20 forming the outer frame of the racket are bent inwards; the flattened base 70 of the suspension hook 72 is held in the required position by the 5 ends 20'' of these bent flanges.

5 In the alternative shown in Fig. 8 the hooks 74 are led through the fixed inner and the movable outer frame; these hooks are held in the central groove running round the circumference of the 10 rim either by means of an eye with a pin or by any other suitable manner.

The arrangement as described above enables 15 us to adjust the required tension of the gut stringing of the racket at any time; the racket stringing remaining elastic, whatever the degree of tightening may be, owing to the elasticity of the inflated rubber tube, which at the end of the game may be eased or deflated by merely pressing the button 52 together with the central inner 20 spindle 48 inside the racket handle, thus opening the relief valve 36, through which the air may be entirely or partly let out of the rubber tube or tubes 18; the tension of the gut being there-

by eased. A further advantage of the arrangement is that when the tubes 18 are deflated, the racket may be strung or restrung without special tension or tensioning devices as restringing is carried out preferably when the pressure in the 5 tubes is eased, contrarily to the hitherto current procedure. The rubber tubes may even be completely removed from off the racket when adjusting the gut stringing, in the manner referred to above. 10

What we claim is:

A tennis racket comprising a handle, a substantially oval frame attached to said handle, a pair of rubber tubes, a connecting tube positioned in said handle, a pump comprising a cylinder, a 15 piston and a piston rod all positioned in said handle, a valve connected to said connecting tube and said pump cylinder and means extending through said piston rod for opening said valve to reduce the pressure in said rubber tubes. 20
